UNITED STATES PATENT OFFICE

2,575,400

CRANKCASE BREATHER AND OIL FILLER
PIPE ASSEMBLYWilliam C. Shirk, Julius A. Jacobsen, Charles H.
Shirk, and Raymond C. Jacobsen, Sioux Falls,
S. Dak.

Application May 26, 1947, Serial No. 750,604

1 Claim. (Cl. 183—15)

1

This invention relates primarily to an internal combustion engine breather and oil filler pipe assembly which insures free and constant crankcase ventilation, and in which there is incorporated air cleaning means which serves to prevent the entrance of dirt into the crankcase of the engine on which the assembly is installed.

Many internal combustion engines either have no means for crankcase ventilation or have means which are inadequate. The passage of raw or burned gases past the pistons into the crankcase is considerable, and they carry much moisture which condenses in the crankcase and forms sludge, as well as carrying acids, soot, and lead compounds. Either the outlet pipes or the filters on the inlets of ordinary breathers are ultimately clogged or restricted. Water in crankcase oil, sludge formation, water soaking of oil filter cartridges, corrosion of bearings, and rusting of valve springs and other parts are but few of the occurrences which evidence inadequate crankcase ventilation. Oil is forced through the main crankshaft bearings due to pressure built up in the crankcase because of clogged breather outlet pipes and filters. Rusting or corrosion of parts of the engine ignition system often results from vapors in gases forced into such system from the crankcase because of such clogging.

The primary object of the present invention, therefore, is to provide an engine breather assembly by means of which adequate crankcase ventilation is had, and removal and exclusion of harmful materials from the crankcase is accomplished before they cause trouble.

A further object of the invention is to provide an assembly of the above kind which is so constructed that the same may be easily disassembled and serviced, and in which the filler nipple of the crankcase may be uncovered so that oil may be introduced into the crankcase of the engine on which the assembly is installed without disturbing said assembly.

Another object of the invention is to provide an assembly of the above kind which is comparatively simple in construction, convenient to use, and highly efficient in use.

The exact nature of the present invention will become apparent from the following description when considered in connection with the accompanying drawings, in which:

Figure 1 is a perspective view of a breather and oil filler pipe assembly constructed in accordance with the present invention.

Figure 2 is an enlarged central vertical section of the assembly shown in Figure 1, partly broken away and with the filler cap removed.

2

Referring in detail to the drawings, the present assembly includes a hollow body 5 in the form of a small tank having a depending bottom nipple 6 at one end adapted to be telescoped within the oil filler nipple 7 of an engine crankcase. A depending open-ended tube 8 is carried by the other end of the body 5 and has its upper end extended through and above the bottom of the body 5. At its lower end portion, the tube 8 is provided with a circumferential series of elongated longitudinal slots 9 covered by an internal strainer screen 10.

A tubular coarse mesh strainer screen 11 is fitted and secured on a slotted tube 12 which is secured at its upper end against the bottom of the body 5 and is disposed in spaced concentric and surrounding relation to the tube 8. A jar 13 or equivalent receptacle encases the major lower portions of the tube 8 and the screen 11, and it is adapted to contain a body of oil to a level substantially at the top of the slots 9 and screen 10.

A cap 14 for jar 13 is carried by and depends from the body 5 in spaced concentric and surrounding relation to the upper portion of the screen 11, and is provided above the top of said jar with a circumferential series of openings 15. Means, such as a hinged bail 16 provided with a cam lever 17 arranged to engage the top of the body 5, is provided for removably clamping the jar 13 in place with its neck within the lower portion of cap 14. The body 5 has a top filler opening 18 in line with the nipple 6, and a removable substantially air tight cap 19 is provided for the opening 18. The arrangement is

such that upon removal of the cap or closure 19, oil may be poured through the opening 18 so that it will pass into and through the nipple 6, into the engine crankcase, without any danger of oil finding its way into the tube 8. At the same time, when the engine is in operation, air may be drawn into the crankcase through the slots 15 of cap 14, screens 11 and 10, tube 8, body 5 and nipple 6, and gas and vapor may be forced from the crankcase through the same elements in a reverse direction.

A horizontal annular baffle or partition ring 20 is provided between the tubes 12 and 8, and may be carried by either of these elements. This baffle or partition 20 is shown as fitted and secured on tube 8 at a point below the neck of jar 13 and above the slots 9, and it causes the air, after passing inwardly through screen 11 from slots 15 to pass outwardly through the screen 11, then inwardly through the lower portion of the latter, and then through the body of oil in jar 13 and screen 10. In this way, effective removal

of dust and other foreign matter from the air is effected, fine particles being removed in passage of the air through the body of oil in the jar and the screens 10 and 11. As the air and the gas and vapors flow in reverse directions during the breathing action of the engine, the surfaces of the screens will be automatically kept clear of foreign matter and the latter will readily settle, together with moisture, to the bottom of jar 13. As the jar 13 is transparent, it can be readily seen when removal of water or sediment is desirable and when the supply of oil in the jar needs changing. It will be particularly apparent that the present invention excludes dirt and other foreign matter and provides free exit of gases and vapors from the engine crankcase, and that oil may be introduced into the crankcase without disturbing the assembly.

As shown, the neck of jar 13 has an external flange 21, and the bail 16 is pivoted to a band 22 clamped on said neck beneath said flange. The cap 14 is seated on a gasket 23 disposed on flange 21, and the slotted portion of this cap is above the upper edge of the jar neck. The closure 19 is similar to those commonly employed on automobile gas tanks and radiators, and the cam of lever 17 seats in a depression 24 provided in the top of body 5. Body 5 is shown as made of a sheet metal shell 25 having its edge spun around a bottom sheet metal wall 26 as at 27. The tube 8 has an external shoulder 28 near its upper end, and the wall 26, top of cap 14 and inturned flange 29 on the upper end of tube 12 are clamped between this shoulder 28 and outwardly and downwardly bent tongues 30 on the projecting upper end of tube 8. A gasket 31 is disposed on tube 8 between the wall 26 and the top of cap 14.

In using the device, the oil is splashed about in the jar 13 and is directed downwardly by baffle 20 onto the screens 10 and 11 so as to maintain thin films of oil on the latter at all times. These oil films prevent dust and the like from passing inwardly through the screens. Air and vapors freely pass in and out or in opposite directions through the device, so that undesirable and dirty vapors may freely pass from the engine crankcase and only clean air is admitted to the crankcase. Under these circumstances, the life of the ordinary oil filter used in the engine lubricating system is greatly prolonged. Also,

5

development of crankcase pressure and its attendant deleterious effects are avoided.

From the foregoing description, it is believed that the construction, operation and advantages of the present invention will be readily understood and appreciated by those skilled in the art. Modifications and minor changes in details of construction are contemplated, such as fall within the scope of the invention as claimed. For instance, the device may be used as an air filter for a carburetor by telescopically assembling the nipple 6 to the air inlet nipple of the carburetor.

Having described the invention, what is claimed as new is:

15

In an assembly of the type described, a hollow body having a depending bottom nipple at one end adapted to be telescopically assembled to the oil filler nipple of an engine crankcase, a depending open ended tube carried by the other end of and communicating with said body, said tube having an imperforate upper portion and provided at its lower portion with a strainer screen, a tubular strainer screen carried by and depending from the bottom of said body in spaced concentric and surrounding relation to said tube and its strainer screen, a cap secured on the bottom of said body and having a cylindrical wall disposed in spaced concentric and surrounding relation to the upper portion of said tubular strainer screen and provided with openings in its upper portion, an oil containing member attached to said body, said tube and tubular screen extending into and adjacent the bottom of said oil containing member.
